SAILBOAT

Charles H. Jones, Jr., Oak St., Lunenburg, Mass.

Filed Feb. 19, 1959, Ser. No. 54,678

Term of patent 14 years

(Cl. D71—1)

FIG. 1.

Fig. 1 is a side elevation of a sailboat showing my new design;

Fig. 2 is a top plan view thereof with the mast, sail and ropes omitted for convenience of illustration; and

Figs. 3 to 8, inclusive, are sectional views taken, respectively, on the lines 3—3 to 8—8, inclusive, of Fig. 2.

The grooved pattern of the diamond-shaped mesh portion as shown in Fig. 2 is continuous throughout said portion.

I claim:

The ornamental design for a sailboat, as shown and described.
